UNITED STATES PATENT OFFICE.

EDWARD H. PARKER, OF NEW BRITAIN, CONNECTICUT.

FIREMAN'S HELMET-LAMP COMBINATION.

Application filed April 18, 1924. Serial No. 707,356.

To all whom it may concern:

Be it known that I, EDWARD H. PARKER, a citizen of the United States, residing at New Britain, in the county of Hartford and State of Connecticut, have invented certain new and useful Improvements in Firemen's Helmet-Lamp Combinations, of which the following is a specification.

My invention relates to improvements in firemen's helmet-lamp combinations of the form comprising a fireman's helmet that is provided with an electric lamp and means for operating and controlling the same, and the object of my improvement is to produce a fireman's helmet that is equipped with an incandescent lamp in which the lamp is supported from the front portion of the brim of the helmet and the control switch is located to one side and also is supported from the brim, the battery being housed within the body, and in which the lamp and adjacent parts that are generally exposed are provided with a protecting cap that serves as a water-shed.

25 In the accompanying drawing:

Figure 1 is a front elevation of my improved fireman's helmet-lamp combination.

Figure 2 is a side elevation of the same.

Figure 3 is a plan view of the same.

30 Figure 4 is a fragmentary bottom view.

Figure 5 is a sectional view on an enlarged scale on the line 5—5 of Fig. 3, with certain parts broken away.

Figure 6 is a rear view of the lamp unit 35 with the protective casing removed.

Figure 7 is a perspective view of the protective casing.

Figure 8 is a front elevation of the lamp unit.

40 Figure 9 is a plan view of the blank for the holding ring.

My improved fireman's helmet-lamp combination comprises a fireman's helmet 10 that is equipped with an incandescent lamp 11 and means for operating and controlling the latter.

The lamp 11 is supported by means of a suitable holding and supporting structure that is designated as a whole by the character 50 ter 12 and is mounted upon the upper face of the front end portion 13 of the brim 14 of the helmet 10.

A dry cell battery 15 is housed within the crown portion 16 of the helmet 10, at 55 the top portion thereof, and is held in place by means of a strap 17. Conductors 18

lead from the battery 15 along the inner face of the front portion of the crown portion 16 and are connected one to one of the terminals for the lamp 11 and the other to 60 the control switch 19. Said switch 19 is located on the under face of the brim 14 and on the left side and adjacent the front. Said switch 19 comprises a moving member 20 that is adapted to be slid back and forth for limited movement along a slot 21 to effect the closing and opening of the electric circuit for operating the lamp 11 from the battery 15.

The helmet body or crown 16 is provided 70 with a perforation 22 for the conducting wires and the location thereof is back of the shield structure 23.

The lamp supporting structure 12 comprises a plate-like bracket 24 that extends 75 upwardly from the brim 14 and that has at the lower end a pair of forwardly directed branches 25 in the form of supporting feet that are secured to the brim 14.

The body portion 26 of the bracket 24 80 has an opening 27 for admitting the screw-threaded base portion 28 of the lamp 11 and mounted upon the rear face of said body portion 26 is a spring contact finger 29 that has the free end in registration 85 with said opening 27 for making contact with the lamp. A screw 30 that is provided with a nut 31 serves to hold the spring contact finger 29 in place, insulating means of ordinary form being provided between these parts and the bracket body 26.

Said body 26 may have also, as shown, a plurality of openings 32 for holding prongs 33 that are provided as integral projections on the annular support or base 34 for the lamp supporting shell 35.

Said annular base 34 is mounted on the front face of the body 26 and the shell 35 is secured to the periphery thereof. Said shell 35 is generally of cylindrical form, extends forwardly from the base 34, is formed of light sheet or tubular material, and the front portion 36 is shaped to provide a screw-thread, as is common. The parts that cooperate with the shell 35 are also ordinary. These comprise the lens 37; the exterior screw-threaded retaining sleeve 38; and the interior reflector structure 39, the latter also having the axially positioned screw-threaded nipple structure 40 for receiving the screw-threaded lamp base 28. The reflector struc-

ture 39 is of cupped form; has an annular back wall 41; and the lamp-supporting nipple structure 40 is in the form of an integral rearwardly directed extension of said back wall 41 and in assembled position the middle or end contact of the lamp 11 will engage with the spring contact 29.

The annular shell base 34 has an opening in continuation of the opening 27 and that 10 serves to provide clearance and permitting of relatively free movement in assembling and inserting the lamp in place.

The lamp unit described is mounted on the brim of the helmet, as mentioned, and 15 is positioned in spaced relation to the crown structure 16. Also, the angle between the body 26 of the bracket 24 and the feet 25 may be made such as to direct the rays of 20 light from the lamp in any particular direction desired relatively to the helmet structure generally.

I find it desirable to provide for the spring contact 29 and adjacent parts a protective casing 42 that serves as a housing 25 and water-shed, being adapted to enclose and cover the same.

Said casing 42 is made of sheet metal, has the upper portion 43 of shell-like form such as to fit closely over the opposed portions of 30 the shell 35 and the supporting bracket body 26, has a closed rear wall 44, and has the side walls extended downwardly in parallelism, and the lower portions 45 of said side walls extend downwardly alongside the side 35 edges of the said bracket body 26. Also, said lower portions 45 have the front edge portions 47 in each case separated by a slit 48 from the upper side wall 49 and bent inwardly generally along the connecting line 40 50 so as to provide integral holding wings or spring clips for removably holding the casing 42 in place. Said wings 47 are opposed to and cooperate with the front face of the supporting bracket body 26 and engage 45 by their upper edges 51 with the under side of the lamp shell 35.

The structure described is adapted to be

used with helmets that are of standard form and in common use, the main metal parts are made of aluminum so as to provide a relatively light structure as a whole, the lamp is positioned so as to give an effective light over a limited zone immediately at the front of the helmet, and the direction of the beam of light with the helmet in the normal position is preferably appreciably inclined downwardly from the horizontal. Also, to reduce the weight and size of the battery one is selected to provide only for a few hours' 55 operation. 60

I claim as my invention:—

1. In a fireman's helmet-lamp combination, a helmet having a body and a brim projected forwardly from said body, a supporting plate projected upwardly from and positioned in spaced relation to said body, a lamp housing and supporting structure comprising a barrel-like side wall and a disc-like base at the rear end thereof and having a threaded sleeve for a lamp-base adjacent 70 said base, said base being in face-to-face contact with the front face of said plate, a contact being positioned adjacent said plate at the rear side thereof, and said plate and base having clearance openings in line with said sleeve and contact for the free passage of a lamp-base engaged with said sleeve and co-operating with said contact. 75

2. In a fireman's helmet-lamp combination, a helmet having a brim, a supporting plate projected upwardly from said brim, contact devices positioned at the rear of said plate and a lamp supporting device comprising a lamp shell that is projected forwardly from said plate and located in spaced 85 relation to said brim, and a protecting casing for said contact devices, said casing being of shell-like form, fitting over the opposed portions of said plate and shell, and having a pair of wings that engage by their 90 upper edges with the under side of said lamp shell. 90

EDWARD H. PARKER.
